(57) **CLAIM**

I claim the ornamental design for a combined gaming machine and display, as shown and described.

DESCRIPTION

FIG. 1 is a front perspective view of the combined gaming machine and display in accordance with the new design; FIG. 2 is a side perspective view of the combined gaming machine and display shown in FIG. 1; the other side perspective view is a mirror image thereof;

FIG. 3 is another front perspective view of the combined gaming machine and display; and,

FIG. 4 is a side perspective view of the combined gaming machine and display shown in FIG. 3; the other side perspective view is a mirror image thereof.

The broken line showing of portions of the combined gaming machine and display depicts environment and forms no part of the claim.
